UNITED STATES PATENT OFFICE

BEN VITTO, OF CHICAGO, ILLINOIS

TYMPANI STICK

Application filed November 6, 1931. Serial No. 573,311.

The sticks now used for beating kettle drums consist of handles inserted through the center of cushions in the form of thick disks, so that contact may be made with the 5 membrane of the drum at any point around a disk or head. One of the objections to a stick of this kind is that it does not strike a sharp blow that will produce a clean cut tone; but all of the blows, therefore the tones 10 resulting therefrom, are muffled.

The object of the present invention is to produce a stick which will give all of the advantages resulting from blows struck by a cushion and, at the same time, will cause a 15 sharply defined tone to be obtained upon striking the drum membrane.

With the ordinary stick, the effect of a blow is about the same as would result from the use of a head or striker having a flat 20 striking surface of considerable area, so that the force of the blow is distributed over a considerable area of the membrane of the drum. In accordance with my invention, 25 while retaining the cushioning effect, I produce more nearly a point contact between the stick and the drum head, thereby causing a sharper, clearer tone to be created.

The various features of novelty whereby 30 my invention is characterized will herein- after be pointed out with particularity in the claims; but, for a full understanding of my invention and of its objects and advantages, reference may be had to the following de- 35 tailed description taken in connection with the accompanying drawing, wherein:

Figure 1 is a side view of a stick embodying the present invention; Fig. 2 is an end view, on a larger scale, looking at the left hand or head end of the stick as it appears 40 in Fig. 1; Fig. 3 is a section on line 3-3 of Fig. 2; and Fig. 4 is a cross section through the handle of the stick.

Referring to the drawing, 1 represents a 45 stick of any usual or suitable size and shape. Fastened on one end of the stick is a head in the form of a thick flat slab or block lying in a plane at right angles to the stick and almost entirely on one side of the stick. 50 This head comprises a core 2 of hard mate- 55 rial in the form of a stake or finger. Inclos-

ing the core throughout the greater portion of its length is a pad 3 of comparatively hard cushioning material that covers and extends along two opposed edges and one end of the core. The periphery of the head is formed 55 of a thick strip 4 of comparatively soft cushioning material. The core may conveniently be made of wood, the pad 3 of compacted felt, and the strip 4 of soft felt. The handle 60 is connected to the finger or core at what may be termed the upper end of the head, 65 namely at a point remote from the covered end. What may be termed the lower half of the head is preferably in the form of a disk whose center is at the point of the cov- 70 ered end of the core.

The core may project from the head proper to the opposite side of the stick and be shaped to form a secondary head. Sometimes a composition calls for the striking of 75 wood on the drum, in which case the handles of the sticks have heretofore been employed. However, by projecting the core of my improved stick and forming them into an auxiliary head, a blow may be struck by wood 80 through the mere turning of a stick in the hand about the long axis of the stick and without shifting the stick end for end.

The head of the stick may be weighted and the balance of the stick modified by providing the secondary head with a hole into 85 which may be inserted a block 6 of lead or other suitable material.

The wooden core may be provided with a 90 contracted portion or neck just below the secondary head 5. The two ends of the felt strip 4 may be carried up past this neck and the strip be fastened to the head by means of a cord or thread 7 wrapped around the 95 ends of the strip and the interposed neck portion of the core. When the felt strip becomes worn or soiled, it may quickly and easily be replaced by a new strip, as all that is necessary is to cut the cord or thread to leave the strip free to be removed.

The head may be fastened to the handle in any suitable way. In the arrangement shown, one end of the handle is screw threaded; the screw threaded portion of the handle is passed through a hole in the core; 100

and a nut 8, is applied to the projecting screw threaded end of the handle and locks the head to the handle.

The handle may be of any desired size and shape, as heretofore explained. In some instances it may be advantageous to have it more or less flattened in the zone where it is gripped in the hand, and thereby enable the user always to point the core of the head 10 in the direction in which the blow is to be struck. Thus, for example, the handle may be oval shaped in cross section as indicated at 10 in Figure 4.

It will thus be seen that, because the head 15 of my improved stick contains a hard core that is pointed at the end opposite the striking point on the periphery of the head, the force of a blow struck by the head will be transmitted to the membrane of the drum 20 through a small or concentrated area thereof, whereby a clear sharply-defined tone results. It will also be seen that my stick is extremely simple, and that the striking surface may be replaced or renewed readily and at little 25 cost.

While I have illustrated and described with particularity only a single preferred form of my invention, I do not desire to be limited to the exact structural details thus illustrated 30 and described; but intend to cover all forms and arrangements which come within the definitions of my invention constituting the appended claims.

I claim:

- 35 1. A tympani stick comprising a handle, a flat head fixed on one end of the handle in a plane at right angles thereto; said head comprising a hard central finger-like core, a comparatively stiff cushion on opposite sides 40 of and across one end of the core, the edge of the cushion being curved in the arc of a circle about said end of the core, and a strip of soft cushioning material overlying and extending along the edge of said cushion.
- 45 2. A tympani stick comprising a handle and a flat head arranged in a plane at right angles to the handle; said head comprising a finger of hard material fixed crosswise of said handle at one end of the latter, a cushion 50 of comparatively hard material extending over one end and two opposed sides of said finger, a strip of comparatively soft cushioning material covering the edge of the aforesaid cushion, and the other end of the finger 55 being shaped to form a hammer device.
- 60 3. A tympani stick comprising a handle, a wooden finger fixed crosswise of the handle at one end of the latter, said finger having an opening therein, a weighting element in 65 the form of a block of metal in said opening, a thick flat pad of comparatively hard felt extending over one end of and along two opposed sides of the finger, and a strip of comparatively soft felt covering the outer 70 edge of the layer of hard felt.

4. A tympani stick comprising a handle, said handle having therein a flattened section, a wooden finger fixed crosswise of the handle at one end of the latter, a thick flat pad of comparatively hard felt extending over one 75 end of and along two opposed sides of the finger, and a stick of comparatively soft felt covering the outer edge of the layer of hard felt.

5. A tympani stick comprising a handle, a wooden finger fixed crosswise of the handle at one end of the latter, a thick flat pad of comparatively hard felt extending over one end of and along two opposed sides of the finger, a stick of comparatively soft felt covering the outer edge of the layer of hard felt, and a tie surrounding the ends of said strip 80 and the interposed finger on the side of the handle opposite that on which said pad lies.

In testimony whereof, I sign this specification.

BEN VITTO.
